United States Patent Office

Des. 220,007
Patented Feb. 23, 1971

220,007

PORTABLE PRINTER

Timothy F. Donovan, Huntington, and William L. Gamble, Unionville, Conn., assignors to Mite Corporation, New Haven, Conn., a corporation of Delaware

Filed Sept. 25, 1969, Ser. No. 19,297

Term of patent 14 years

Int. Cl. D18—02

U.S. Cl. D64—11

FIG. 1

FIG. 2

FIG. 1 is a perspective view of the top, front and one side of the portable printer embodying our new design, with the removable cover in place;

FIG. 2 is a perspective view of the bottom, rear, and other side of the portable printer with the removable cover in place;

FIG. 3 is a perspective exploded view of the portable printer with the removable cover detached therefrom;

FIG. 4 is a side elevational view of the portable printer with the cover removed; and

FIG. 5 is a rear elevational view of the portable printer with the cover removed therefrom.

We claim:

The ornamental design for a portable printer, as shown and described.
